UNITED STATES PATENT OFFICE.

THOMAS TREGANOWAN AND LEO PAUL O'HARA, OF PITTSBURGH, PENNSYLVANIA.

GARBAGE INCINERATOR.

Application filed April 5, 1922. Serial No. 549,729.

To all whom it may concern:

Be it known that we, THOMAS TREGANOWAN and LEO PAUL O'HARA, citizens of the United States, residing at Pittsburgh, in the county of Allegheny and State of Pennsylvania, have invented certain new and useful Improvements in Garbage Incinerators, of which the following is a specification.

- 10 This invention relates to certain new and useful improvements in incinerators for burning garbage and other refuse of a household or building and has particular reference to that type of incinerator capable of installation in the kitchen of a house or in the kitchen of the different apartments of an apartment house, whereby the garbage or refuse may be burned by the occupant of an apartment.
- 15 20 The primary object of the invention embodies in an incinerator of the type above set forth, the idea of constructing the incinerator or furnace of comparatively few structural elements that are capable of being replaced should damage or injury occur thereto.

The invention further includes the installation of individual incinerators in the kitchens of apartment houses with a single vertical flue aligned with a plurality of incinerators, providing a draught and a single exit or discharge passage for the ashes.

A further object of the invention resides in the provision of an incinerator of the type above set forth wherein the incinerator casing or body portion is formed of fire brick and enclosed by a metal casing or housing spaced therefrom to provide a non-conducting heat space between the fire brick wall and casing.

With the above general objects in view and others that will appear as the nature of the invention is better understood, the same consists in the novel construction, combination and arrangement of parts hereinafter more fully described, illustrated in the accompanying drawings and pointed out in the appended claims.

In the drawings forming a part of this application and in which like designating characters refer to corresponding parts throughout the several views,

Figure 1 is a front elevational view of an incinerator constructed in accordance with the present invention, showing the receiving door for the refuse, the door for

the ash compartment and the gas burner supply pipe.

Figure 2 is a vertical cross sectional view of the incinerator shown in Figure 1, illustrating the bearings for the grate, and the perforated baffle or guide, for the refuse.

Figure 3 is a vertical section view taken at right angles to the form shown in Figure 2, showing the inclined side grates, the wedge-shaped baffle and the burner tubes supporting the inclined grates with the ash-pan disposed beneath the grate.

Figure 4 is a horizontal sectional view taken above the wedge-shaped baffle shown in Figure 3, illustrating the inclined side grates and the perforated baffle.

Figure 5 is a detail sectional view showing angle bar mounting for one end of the pivoted grate, and the burner tubes, and

Figure 6 is a detail sectional view showing the incinerator installed in the kitchen wall of an apartment kitchen with the flue associated therewith extending to the lower apartments and the ground floor.

Referring more in detail to the accompanying drawings and particularly to Figures 1 to 5, there is illustrated an incinerator to be placed in the basement of a building to receive garbage or other refuse, through a feeding flue, while in Figure 6 of the drawings, the incinerator is shown as installed within the kitchen of an apartment with the bottom wall thereof either provided with an ash-pan or an opening, to permit the collection or discharge of the ashes within the flue. In the incinerator shown in Figures 1 to 5, the same embodies side and top walls 1 and 2, formed of fire-brick, the same being supported on a base-wall 3, carrying mounting feet 4. The fire-brick casing is surrounded by a metal housing 5, spaced therefrom by members 6 to 100 provide an intervening air-space 7 constituting a non-conductor for heat resulting from the operation of the device. As shown in Figures 1, 2, 3 and 6 the top wall 2 of the fire-brick and the casing 5, is provided with an opening 8 to permit the escape of smoke and fumes and also to provide a feed opening when the incinerator is installed in the basement of a building.

The front wall of the incinerator as shown in Figure 1 is provided with a refuse-receiving opening closed by a door 9, the

bottom wall 3 supporting an ash-pan or receptacle 10 accessible by the ash-door 11 as illustrated.

- The burners and grate elements contained 5 within the incinerator include a mounting angle iron 12 shown more clearly in Figures 2 and 5, the same being of H-formation and supporting the stud end 13 of the pivoted grate 14, the opposite end thereof 10 carrying a rod 15 projecting through the front wall of the incinerator casing as shown in Figures 1 and 2, for the application of an operating key or handle 16, the grate 14 being disposed between the receiving 15 opening and the ash-compartment of the incinerator. As shown in Figure 3, a strap iron 17 supports the forward end of the grate in addition to the front wall of the incinerator.
- 20 A pair of inclined side grates 18 having the upper ends thereof engaging the opposite side walls of the incinerator are provided upon the lower ends with brackets 19 that rest upon burner tubes 20 as clearly 25 shown in Figures 3 and 5 with the lower ends 18' of the inclined grates projecting inwardly of the burner tubes and overlying the jet openings 20' to protect the burners from ashes or other refuse falling thereon 30 and clogging the jets. The burner tubes 20 are supported in socket portions 12' provided in the channel brace 12, while the opposite ends of the burner tubes are supported in the strap bearing 17.
- 35 As shown more clearly in Figures 1 and 2, a gas supply pipe 21 is supported exteriorly of the front wall of the incinerator and has valve connections 22 with the burner tubes 20.

- 40 A wedge-shaped baffle is disposed between the lower ends of the inclined side grates 18, the same having perpendicular end walls 23 and inclined perforated side walls 24 with the adjacent edges of the end walls 23 secured 45 for an interlocking engagement, the rear ends of the side walls 24 carrying pins 25 for pivotal mounting in the channel brace 12 while pins carried by the opposite ends of the side walls 24 are supported in brackets 26 adjacent the strap bearings 17.

From the above detailed description of the device it is believed that the construction and operation thereof will at once be apparent, it being noted that the incinerator 55 is of extremely simple construction, the few parts united to constitute an operative device being easily and quickly replaced without necessitating the employment of skilled labor.

- 60 When the incinerator is installed in the basement of a building, the opening 8 in the upper end thereof communicates with an outlet flue and garbage or other refuse is introduced through the door opening 9, the same falling upon the perforated wedge-

shaped baffle for reception of the inclined side grates 18. The burner tubes 20 are suitably ignited, and the jets issuing therefrom will be directed inwardly of the wedge-shaped baffle to escape through the 70 perforations therein and efficiently burn the refuse, the ashes falling through the grates and into the pan 10 at the lower end of the incinerator. The grate 14 may be shifted 75 to discharge any ashes that might collect thereon, while the smoke and fumes from the incinerator will escape through the opening 8 at the upper end thereof and into the flue.

The incinerator is illustrated in Figure 6 80 as installed in the wall of a kitchen in an apartment or other house, the wall being designated by the numeral 27 having a flue passage 28 therein with the incinerator entirely disposed within the flue with the front wall thereof being substantially flush with the face of the kitchen wall. In installations of this character, an opening may be provided in the bottom wall of the incinerator, and the ashes permitted to fall therefrom and be removed through the side opening 29 at the lower end of the flue.

While the form of the invention herein shown and described is what is believed to be the preferred embodiment thereof, it is nevertheless to be understood that various forms, modifications and arrangements of the parts may be made without departing from the spirit and scope of the invention as claimed.

What we claim as new and desire to secure by Letters Patent, is:—

1. In an incinerator of the type described, a casing, burner tubes extending transversely of the casing, strap irons at opposite sides of the casing forming bearings for said tubes, and inclined side grates engaging the side walls of the casing at the upper ends and supported at their lower ends on the burner tubes and forming an interlocking connection therewith, and a two-part wedge-shaped baffle having the parts pivoted at their lower ends in the side walls of the casing and positioned between the burner tubes and grate bars.

2. In an incinerator of the type described, a casing, burner tubes extending transversely of the casing, strap irons at opposite sides of the casing forming bearings for said tubes, inclined grates engaging the opposite sides of the casing, bracket arms carried by the lower faces of the grates, adjacent the lower ends thereof supported on the burner tubes and forming an interlocking connection therewith, and a two-part wedge-shaped baffle having the parts pivoted at their lower ends in the side walls of the casing and positioned between the burner tubes and grate bars.

3. In an incinerator of the type described,

a casing, burner tubes extending transversely of the casing, strap irons at opposite sides of the casing forming bearings for said tubes, inclined grates engaging the opposite sides of the casing, bracket arms carried by the lower ends of said grates supported on the burner tubes with the lower end of the grates extending inwardly of the burner tubes to protect the jet openings thereof and forming an interlocking connec-

tion therewith, and a two-part wedge-shaped baffle having the parts pivoted at their lower ends in the side walls of the casing and positioned between the burner tubes and grate bars.

In testimony whereof, we affix our signatures.
